SERVICE VALVE LINE CLAMP

John W. Mullins, P.O. Box 20524,
Oklahoma City, Okla. 73120

Filed Dec. 26, 1968, Ser. No. 15,123

Term of patent 14 years

Int. Cl. D23—01

U.S. Cl. D23—19

FIG. 1

FIG. 2

FIG. 3

FIG. 4

FIG. 6

FIG. 1 is a perspective view of a service valve line clamp embodying my new design, the line and valve being shown in broken lines for illustrative purposes only.

FIG. 2 is a top view of FIG. 1.

FIG. 3 is a bottom view of FIG. 1.

FIG. 4 is an elevational view.

FIG. 5 is an elevational view rotated 30° to the right from the position shown by FIG. 4.

FIG. 6 is an elevational view rotated 30° to the left from the position shown by FIG. 4.

I claim:

The ornamental design for a service valve line clamp, substantially as shown and described.
